Arthur Middleton

UNITED STATES PATENT OFFICE.

JUDSON A. DE CEW, OF MOUNT VERNON, NEW YORK.

BEATING ENGINE.

Application filed January 29, 1920. Serial No. 354,992.

To all whom it may concern:

Be it known that I, JUDSON A. DE CEW, a citizen of the Dominion of Canada, residing at Mount Vernon, New York, have invented 5 new and useful Improvements in Beating Engines, of which the following is a specification.

This invention relates to beating engines used in the making of paper and its object is 10 to devise a beater that is smaller or covers less floor space than is usual and at the same time one that is more efficient in its treatment of the paper stock.

To this end the invention consists in a vat 15 provided with the usual beater roll and a mid-feather co-acting with the roll, but the elements are so arranged that the circulation of the stock to and from the roll is in a vertical plane instead of in the usual horizontal 20 plane and a further important feature is that the roll is used to elevate the stock and to change the direction of the flow. Moreover, the mid-feather is arranged substantially horizontally and adapted to have the 25 stock pass therealong and therefrom by gravity. This arrangement reduces the retarding action of friction between the stock and the sides of the vat to a minimum.

I have illustrated the preferred embodiment 30 of my invention in the accompanying drawing in which

Figure 1 illustrates a vertical section through my machine, and

Fig. 2 shows a plan view.

35 In the drawings, the numeral 11 indicates the vat having sides 12 and 13. 14 indicates a straight end and 15 an end curved to correspond with the curvature of the beater roll 16. Between the roll 16 and the straight end 40 14, a mid-feather 17 extends substantially horizontal but inclined slightly downwardly and has at its end adjacent the roll 16 a deflector extension 18 substantially triangular in cross section. The free end 19 of the mid- 45 feather is sufficiently spaced from the straight end 14 of the vat to permit the free passage of the paper stock therebetween. Means for adjusting the degree of inclina- 50 tion of the mid-feather may be provided such as the screws 20 co-acting with exten-

sions 21 on the mid-feather to raise and lower it about its pivot 22.

In operation, the paper stock passes under the mid-feather 17 until the deflector guides it toward and under the roll 16 where 55 it is duly acted upon by the roll and its co-acting parts. It is then elevated by the roll and deposited on top of the mid-feather 17 where its tendency is to accumulate. This accumulation tends to push the stock along 60 the incline of the mid-feather until it falls off the end thereof due to gravity, to the bottom of the vat where it flows along toward and under the roll again. The deflector extension 18 is for directing the returning 65 stock directly to the beating point of the roll instead of letting it contact with the knives before they reach the beating point. In this way, unnecessary friction with the downwardly moving knives is prevented and 70 less power is required to drive the roll.

Where the circulation of the stock is horizontal, the entire force for the circulation must be supplied by the roll. Further, the retardation of the stock flow around the 75 mid-feather at the ends of the vat is considerable. In the present invention, the roll only elevates the stock and gravity is depended upon to complete the circulation, which results in a decided saving in power 80 and the vertical arrangement of the flow makes possible a vat of normal capacity but which takes up much less floor place than normally. The inclination of the mid-feather is made adjustable to suit different 85 consistencies of stock.

What I claim is:

1. A beating engine having a vat, a beater roll at one end thereof, a substantially horizontal mid-feather extending from the roll 90 toward the opposite end of the vat, and a substantially triangular deflector adjacent the roll, depending from the mid-feather.

2. The device of claim 1 in which the face of the deflector nearest the roll is curved 95 similar to the roll and covers the vertical part of the roll.

3. A beating engine having a vat, a beater roll providing between the vat and the roll a beating point, knives on said roll, and 100

means for preventing the knives from exerting a vertical, downward force upon the stock in the vat.

4. A beating engine having a vat, a beater roll providing between the vat and the roll a beating point, knives on said roll, and means for directing the stock in the vat directly to

the beating point and keeping the stock out of contact with the knives during their vertical downward movement.

In testimony whereof, I have signed my name to this specification this 19th day of January 1920.

JUDSON A. DE CEW.
